UNITED STATES PATENT OFFICE.

JOHN H. BATES, OF CHICAGO, ILLINOIS.

ATTACHMENT FOR PLAYER-PIANOS.

1,390,421.

Specification of Letters Patent. Patented Sept. 13, 1921.

Application filed March 29, 1920. Serial No. 369,651.

To all whom it may concern:

Be it known that I, JOHN H. BATES, a citizen of the United States, and a resident of Chicago, in the county of Cook and State of Illinois, have invented certain new and useful Improvements in Attachments for Player-Pianos, of which the following is a full, clear, and exact description.

The invention relates to attachments for 10 player pianos and more particularly to devices for guiding the perforated sheet or web between the supply and take-up rolls.

The object of the invention is to provide 15 an attachment for this purpose which may be readily applied to and removed from the tracker bar of a player and readily adjusted thereon.

The invention consists in the several novel 20 features hereinafter set forth and more particularly defined by claims at the conclusion hereof.

In the drawings: Figure 1 is an elevation 25 of a portion of a player piano provided with the invention. Fig. 2 is a section taken on line 2—2 of Fig. 1. Fig. 3 is a section taken on line 3—3 of Fig. 2. Fig. 4 is a perspective of a portion of the improved attachment.

The invention is illustrated as applied to 30 a player piano comprising a frame 5 in which the tracker board 6 is secured, a feed-roll 7 radially mounted in the frame and a roll 8 containing the perforated sheet or web 9 which is to be wound upon the roll 7 to 35 operate the web over the ducts in the board 6. Suitable gearing 10 serves to operate the feed roll 7, to wind up the web and also to rewind the web on the roll 8 after it has been played. All of these parts may be of 40 usual construction and operation, as well understood in the art. In practice, the roll 8 is, as usual, removably held in the frame 5.

While the web is being transferred from 45 one roll to the other, there is frequently a tendency of the web to crowd either to one end or the other of the roll on which the web is being wound. This results in wearing or destroying the edge of the web and the object of the invention is to provide an 50 attachment by which this may be prevented.

A cross-bar 11 adapted to rest on top of the

board 6 and posts 12 fixed in the bar 11 form a support for a pair of guides 13 which are adapted to be positioned to guide the edges of the web 9. Each guide 13 has studs 14 55 affixed thereto which are slidable in one of the posts 12. Each post is provided with a nut 15 and a spring 16 around each stud and between the post 12 and guide 13 to press the guide inwardly. The nuts 15 serve as 60 adjustable stops for the guide. Clamps comprising U-shaped members 17 adapted to straddle or extend around the front of the board 6 and thumb-screws 18 serve to adjustably secure the guide-support to said board. 65

When the clamps are loose, the guide-support and guides may be conjointly adjustable laterally to bring the guides into correct position to guide the web. By adjusting the nuts 15, the spacing of the guides may 70 be varied according to the width of the web.

The invention exemplifies a simple attachment comprising a pair of guides for the edge of the web which may be readily applied to the tracker board and readily adjusted thereon. 75

The invention is not to be understood as restricted to the details set forth, since these may be modified within the scope of the appended claims, without departing from the 80 spirit and scope of the invention.

Having thus described the invention, what I claim as new and desire to secure by Letters Patent, is:

1. An attachment for player-pianos comprising guides for the edges of the note-sheet, and clamping devices extending around the face of the tracker bar and provided with means between which the tracker-bar will be clamped to secure the 90 guides thereon. 85

2. An attachment for player pianos comprising a pair of guides for the edges of the note sheet, a support at one side of the tracker-bar extending between the guides 95 and on which both of the guides are mounted, means for securing the support to the tracker bar comprising a clamping-device extending across the face of the tracker bar, and provided with means between which the 100 tracker bar will be clamped to secure the support thereon.

3. An attachment for player pianos comprising the combination of a pair of guides for the edges of the note sheet, a supporting bar on which both guides are mounted and fitting against one side of the tracker bar, and clamping devices secured to said bar and extending around the face of the tracker
5. bar, and screws carried by said members and adapted to press against the other side of the tracker bar so that the latter will be clamped 10 in said devices to secure the support on the tracker-bar.

JOHN H. BATES.
